LIFE SAVING DEVICE

George A. Evenden and George F. Wilson,
Hamilton, Ontario, Canada

Application July 30, 1934, Serial No. 737,527

8 Claims.

(Cl. 9—17)

This invention relates to improvements in pneumatic life saving devices for the personal use of swimmers and others similarly exposed to water perils, and consists of a collapsible or foldable bag composed of impermeable material adapted to be normally folded and carried in a suitable location about the costume or otherwise.

One important object of the invention is to provide an emergency pneumatic device for bathers, boatmen and the like adapted in an emergency to be brought into use quickly to buoy the user without the preliminary necessity of manually effected inflation.

Another important object is to provide a device of the class specified which will be substantially delitescent when stowed for emergency use.

Another important object is to provide a normally latent device for the purpose specified which will be self-inflatable when desubmerged.

Another important object is to provide a device of the kind described which will be simple, durable, effective, and inexpensive to manufacture.

With the above and other objects in view as will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

Figure 1 is an elevation of a life saving device as constructed in accordance with this invention;

Figure 2 is a median cross-section of Figure 1;

Figure 3 is a bottom view;

Figure 4 is a representation of a distressed bather with the device extended above the surface and inflated; and,

Figure 5 is a representation of an erstwhile distressed bather with the device in use as a buoy.

In its present embodiment the invention consists of a bag 10 formed of flexible impermeable material such as, for instance sheet rubber, or waterproofed fabric. This material should not only be durable but light since the bag is normally folded into a pack for stowing conveniently about the bathing costume.

Because of the amorphism of the bag when folded or packed it is not shown in that position on the drawing.

The bag is preferably provided with a stiffening ring 12 at or near its mouth margin or rim. This ring is relatively elastic and may be formed of light rubber tubing or strap enclosed in the tubular bag hem 13 as shown, or attached to the

bag in any approved manner. The relatively stiffened portion of the bag is therefore capable of being folded together with the bag, but when the bag is released from its pack form and extended above the surface the ring 12 tends to open the mouth for the free admission of air and furthermore lends an otherwise deficiency of weight to the mouthed portion of the bag.

Athwart the ring 12 is a relatively stiff but elastic hand grip 14 which is similarly capable of being folded together with the bag.

In use, the closed end or tip of the bag which has presumably been left in the most conveniently accessible position is grasped by one hand and whipped or projected into the air in an inverted depending position. It immediately unfolds, its mouth opening under the urge of the stiffening ring, when it then spreads with the influx of air. The hand grip may then be grasped by the other hand, and with both hands the bag may be lowered mouth down to the surface, or it may be first dropped to the surface before the hand grip is taken hold of. When the rim of the bag has thus engaged the surface of the water, or slightly submerges as it is more or less bound to do under the weight of the user, no air or in any event only an inconsequential amount of air can escape. The above procedure is of course practically instantaneous. The bag thus acts as a buoy to which the erstwhile distressed bather may cling by means of the hand grip until the arrival of assistance or until he can work his way to shallow water. The capacity of the bag of course is such as to contain more than sufficient air to keep the user afloat.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a life saving device consisting of an open ended impervious bag, a relatively stiff elastic ring at the mouth of said bag, said bag and ring being adapted to be normally folded into a pack, said bag being adapted to open under the urge of said ring and to receive air from the atmosphere when projected from the water, said bag being adapted to retain at least most of its air content

- while in contact with the water rimwise and also while partially submerged and while wholly submerged rim down, and having the capacity for sufficient air to keep a person afloat when it is 5 grasped by such person.
2. In a life saving device consisting of an impervious bag having an open mouth, a relatively stiff elastic ring encircling the mouth of said bag, said bag and ring being adapted to be normally folded into a pack, said bag being adapted to expand under the urge of said ring and to receive air through said mouth from the atmosphere when projected from the water, said bag being adapted to retain at least most of its air content 10 while in contact with the water mouth down and also while partially submerged and while wholly submerged mouth down, and having the capacity for sufficient air to keep a person afloat when it is 15 grasped by such person.
3. In a life saving device consisting of an open ended impervious bag normally adapted to be folded into a constricted pack, the constriction being effected by cramped confinement, a relatively stiff elastic ring associated with said bag and adapted to fold therewith, said ring being adapted to effect opening of the bag automatically upon manually effected relaxation of the constraint, the opened bag being adapted to receive air from the atmosphere when projected from the water, said 20 bag being adapted to retain at least most of its air content while in contact with the water rimwise and also while partially submerged and while wholly submerged rim down, and having the capacity for sufficient air to keep a person afloat 25 when it is grasped by such person.
4. In a life saving device consisting of an open ended impervious bag normally folded into a constricted pack, a relatively stiff elastic ring associated with said bag and adapted to be folded therewith, said ring being adapted to effect opening of the bag automatically upon manually effected relaxation of the constraint, the opened bag being adapted to receive air from the atmosphere when projected from the water, said bag 30 being adapted to retain at least most of its air content while in contact with the water rimwise and also while partially submerged and while wholly submerged rim down, and having the capacity for sufficient air to keep a person afloat 35 when it is grasped by such person.
5. In a life saving device consisting of an impervious bag having an open mouth and adapted to be folded normally into a constricted pack, the constriction being effected by cramped confinement, a relatively stiff elastic ring associated with said bag and adapted to fold therewith, said ring being adapted to effect opening of the bag automatically upon manually effected relaxation of the constraint, the opened bag being adapted to receive air from the atmosphere when projected from the water, said bag 40 being adapted to retain at least most of its air content while in contact with the water mouth down and also while partially submerged and while wholly submerged mouth down, and having the capacity for sufficient air to keep a person afloat when it is 45 grasped by such person.
6. In a life saving device consisting of an impervious bag having an open mouth and normally folded into a constrained pack, a relatively stiff elastic ring associated with said bag and adapted to fold therewith, said ring being adapted to effect opening of the bag automatically upon manually effected relaxation of the constraint, the opened bag being adapted to receive air through 50 said mouth from the atmosphere when projected from the water, said bag being adapted to retain at least most of its air content while in contact with the water mouth down and also while partially submerged and while wholly submerged mouth down, and having the capacity for sufficient air to keep a person afloat when it is 55 grasped by such person.
7. A life saving device consisting of an impervious bag having an open mouth and provided with a relatively stiffened elastic banded portion concentric with said mouth, said bag including said banded portion being adapted to be folded normally into a constricted pack, the constriction being effected by cramped confinement, said banded portion being adapted to effect opening of the bag automatically upon manually effected relaxation of the constraint, the opened bag being adapted to receive air through said mouth from the atmosphere when projected from the water, said bag 60 being adapted to retain at least most of its air content while in contact with the water mouth down and also while partially submerged and while wholly submerged mouth down, and having the capacity for sufficient air to keep a person afloat when it is 65 grasped by such person.
8. A life saving device consisting of an impervious bag having an open mouth and provided with a relatively stiffened elastic banded portion concentric with said mouth, said bag including said banded portion being adapted to be folded into a constricted pack, said banded portion being adapted to effect opening of the bag automatically upon manually effected relaxation of the constraint, the opened bag being adapted to receive 70 air through said mouth from the atmosphere when projected from the water, said bag being adapted to retain at least most of its air content while in contact with the water mouth down and also while partially submerged and while wholly submerged mouth down, and having the capacity for sufficient air to keep a person afloat when it is 75 grasped by such person.
